UNITED STATES PATENT OFFICE.

GUSTAF I. SILBERT, OF CHICAGO, ILLINOIS, ASSIGNOR, BY MESNE ASSIGNMENTS, TO CHI-ILL ELECTRIC COMPANY, OF CHICAGO, ILLINOIS, A CORPORATION OF ILLINOIS.

COMBINATION-LOCK FOR PLUG-AND-SOCKET FIXTURES.

1,073,295.

Specification of Letters Patent. Patented Sept. 16, 1913.

Application filed February 20, 1911. Serial No. 609,657.

To all whom it may concern:

Be it known that I, GUSTAF I. SILBERT, a citizen of the United States, and a resident of Chicago, in the county of Cook and State of Illinois, have invented certain new and useful Improvements in Combination-Locks for Plug-and-Socket Fixtures; and I do hereby declare that the following is a full, clear, and exact description thereof, reference being had to the accompanying drawings, and to the characters of reference marked thereon, which form a part of this specification.

This invention relates to improvements in combination locks for plug and socket electric fixtures, such as electric lamps, plug and cord attachments, adapter fixtures and the like, wherein one member is locked to the other by a combination lock mechanism of the general type shown in my pending application for United States Letters Patent, Serial No. 572,482, filed July 18th, 1910.

Among the objects of the present invention is to provide an improved lock mechanism for such fixtures arranged to avoid the necessity of a dial on one of the parts and a co-operating indicator on the other part to facilitate the release of the locking elements, thereby enabling the locking elements to be released from each other in comparative dark and inaccessible places.

Another object of the invention is to improve the general construction of such locks and the invention consists in the matters hereinafter set forth and more particularly pointed out in the appended claims.

In the drawings,—Figure 1 is a view partially in elevation and partially in section of a lamp base and socket mounting embodying my invention. Fig. 2 is a plan view of the base member of the lamp, with parts broken away. Fig. 3 is a side elevation of the upper part of the lamp base showing the lock tumblers carried thereby. Fig. 4 is a plan view of one of the tumblers and combined spacing ring and tumbler projection. Fig. 5 is a similar view of another tumbler. Fig. 6 is an axial section of the sheet metal socket cup. Fig. 7 is a cross section showing a modified form of clicking member. Fig. 8 is a detail illustrating a modified form of spring-pressed element adapted to co-operate with the clicking member of the base or socket.

As shown in the drawings, 10 designates a porcelain or other insulating body of a socket and 11 designates the base of an electric lamp having a reduced end to enter said socket. The insulating body 10 is recessed at its lower end to receive a sheet metal socket cup 12 which carries on the inner surface of its cylindric wall 15 a series of spaced, angularly separated projections 14 with spaces 16 between them and which constitute the fixed elements of the combination lock. The said cup may be made of sheet metal by a stamping or swaging operation, and the spaced, angularly separated locking projections 14 may be formed therein by shearing the metal of the cylindric wall 15 inwardly as shown in Fig. 6, so as to leave the spaces 16 between said projections.

The base 11 (or other form of plug) is formed at its inner end with a concentric tubular extension or neck 18 which is loosely surrounded by a sheet metal tumbler bearing sleeve 19. The lower end of said sleeve is enlarged at 20 to fit closely in the outer end of the socket cup 12, and said enlarged end 20 is formed with a notch 21 to engage a projection 22 formed on the inner cylindric wall of the cup to prevent the tumbler sleeve from turning in the cup when the base extension is inserted thereinto. Mounted on said tumbler sleeve and free to rotate thereon are one or more tumblers 24, 25, two being herein shown.

26 designates a third tumbler which is fixed to the end of the tubular extension or neck 18 of the base, in a manner hereinafter described, so that said latter tumbler turns with the base extension or neck. The tumblers 26, 25 and 24 are spaced from each other by spacing rings 28, which preferably have the form of thin open rings that may be made of clock spring stock. The lower loose tumbler is spaced from the enlargement 20 of the tumbler bearing sleeve by means of a curved spring wire 30 which is provided at one end with a lug or extension 31 adapted to extend upwardly through one of a plurality of angularly separated openings 32 of the tumbler 24. Arranged over the upper fixed tumbler 26 is a second curved spring wire 33 that is provided with a downwardly extending end or lug 34 which is adapted to extend through one of a plurality of angularly separated openings 110

35 in the upper fixed tumbler 26. The said extensions or lugs 31 and 34 of the wires 30 and 33 are adapted to coöperate with lugs on the intermediate tumbler 25, consisting 5 as herein shown of a pin 36 which extends through a suitable opening in the intermediate tumbler. The lugs 31 and 34 constitute tumbler controlling lugs or elements by which the freely rotative tumblers 24 and 10 25 are controlled through the medium of the fixed tumbler 26 and its lug 34 in a manner familiar in combination or permutation locks.

The combination of the lock may be 15 changed by removing the wires 33 and 30 from their tumblers and inserting their lugs through other openings 32 and 35 of the tumblers, as will be evident, thereby providing for a wide range of variation of adjustment. The said tumblers 24, 25 and 26 are provided with a plurality of peripheral, angularly separated notches 38 adapted to pass over the projections or shoulders 14 of the socket cup 12 when said notches are 25 arranged in line with each other, as shown in Fig. 3. When the lamp is to be locked to the socket, the said notches are thus arranged in line with each other and the base or plug extension is inserted into the socket. 30 Thereafter the base is turned or rotated to angularly shift the tumblers into the notches 16 between the projections 14 and thereby lock the base in the socket. In this manner the lamp base or plug is locked in the socket 35 and can be released only by angular transposition of the tumblers in a predetermined concerted order for which the tumblers have been previously arranged. In rotating the lamp base or plug to transpose the tumblers 40 to releasing position, the innermost tumbler 26 is rotated directly by the lamp base, and the loosely mounted tumblers 24 and 25 are rotated indirectly thereby through the interaction of the lugs 31, 34 and 36 until the 45 notches 38 of the tumblers are brought into line with the projection 14 of the socket cup.

In order that the tumblers of the lamp base or plug may be thus angularly transposed without the necessity of employing a 50 dial on the one part to coöperate with a pointer or indicator on the other part, one of said parts is provided with an annular notched member and the other part is provided with a yielding click device arranged 55 to pass over said notched member in such a way that upon rotation of one of the parts the passing of the click device over the notched member will audibly indicate the extent of angular movement of the movable 60 part; and the relation of the parts are so arranged that the movable part is turned a predetermined angular distance in one direction and a predetermined distance in the other direction, as indicated by the clicking 65 sound as the click device passes over the

curved notched member, until the notches of the tumblers have been brought into line with the projections 14 of the socket cup.

As herein shown (Figs. 1, 2 and 3) 40 designates a sheet metal ring provided with a flange 41 which closely fits over the upper end of the base extension or neck 18 and is fixed to turn therewith. The horizontal portion of said ring is provided throughout its principal part with a plurality of angularly spaced notches 42, and with a smooth or unnotched portion 43. The upper end of the cup is provided with a clicking device consisting of a spring 44 having a downwardly turned, rounded terminal 45 adapted to be pressed by the resiliency of the spring into engagement with the notched ring 40. The terminal end 45 of the spring permits the notched ring or member to be turned in either direction.

The parts are so arranged that the spring 44 produces an audible click each time it passes over one of the notches. When it passes over the smooth or unnotched portion no clicking is heard. Therefore, starting with the spring on the unnotched portion 43 of the ring 40 the base or plug is turned in one direction until a predetermined number of clicks are heard, is thence turned in the other direction for a predetermined 95 number of clicks, and so on until the notches 38 of the tumblers are brought into line with each other and with the projections 14 of the socket cup 12, whereupon the base or plug may be removed from the socket. The 100 audible clicking provided for enables the lock to be released without the necessity of employing a dial on one of the movable parts to coöperate with a pointer or indicator on the other part, thereby permitting 105 the lock to be released in dark and other relatively inaccessible places.

The notched clicking ring 40 may be attached to the extension or neck of the base by having the end of the base extension flanged thereover, as indicated at 50 in Fig. 1, with the ring notched to press the metal of the neck therein to afford an interlocking connection, as indicated at 51. The innermost tumbler may likewise be notched 110 to receive outwardly pressed parts 52 of the neck to fix said tumbler thereon. Obviously the said clicking ring and innermost tumbler may be otherwise non-rotatively fixed to the extension or neck of the base or plug. Instead of employing the leaf spring 44 as the clicking device, I may provide the plunger form of device 53 shown in Fig. 8, which is backed by a spring 54 located in a socket in the socket body 10.

In Fig. 7 is shown a form of notched ring 55 wherein the notches 56 for engagement with the clicking device are formed on the edge of the ring. In this form of ring it will usually be made of somewhat heavier 130

gage than in the device shown in the other figures.

One side of the lamp (or plug) circuit is closed through the socket cup 12 and through bolts 60 by which the socket cup 5 is attached to the insulating socket body, and the other side of the circuit is closed through a yielding terminal 61 and a sleeve surrounding the outer end thereof and bearing on the central terminal of the lamp base, 10 as shown in Fig. 1.

The construction may be varied within the scope of the invention and I do not wish to be limited to the details shown except as 15 such limitations are imposed by the prior art. For instance, the clicking device and notched ring may be reversed with the former on the plug or base and the latter on the socket.

20 I claim as my invention:—

1. In an electric plug and socket fixture, a socket, a fixed cup shaped member therein provided at its annular wall with angularly spaced locking projections, a spring controlled member extending through the end 25 wall of the cup shaped member, a plug adapted to enter said cup shaped member and provided with tumblers to engage said projections, and a ring carried by said plug

and provided at its inner end with an arc 30 shaped smooth portion and with an arc shaped notched portion connecting the ends of said arc shaped smooth portion, said smooth and notched portions being adapted to be engaged by said spring controlled 35 member in the rotation of the plug.

2. In an electric plug and socket fixture, a socket, a fixed cup shaped member therein provided at its annular wall with angularly spaced locking projections, a spring attached to the end wall of said cup shaped member and having a terminal which extends inwardly beyond said end wall and a plug adapted to enter and to be locked to the angularly spaced projections of said cup 40 shaped member and provided with a circular ring member having a smooth and a notched portion for engagement with the terminal of said spring.

In testimony, that I claim the foregoing as 50 my invention I affix my signature in the presence of two witnesses, this 16th day of February A. D. 1911.

GUSTAF I. SILBERT.
